CLAIM

I claim the ornamental design for a remote control, as shown and described.

DESCRIPTION

FIG. 1 shows a front perspective view of the remote control; FIG. 2 shows a front view of the remote control; FIG. 3 shows a rear view of the remote control; FIG. 4 shows a first side view of the remote control; FIG. 5 shows a first side view of the remote control; FIG. 6 shows a top view of the remote control; and, FIG. 7 shows a bottom view of the remote control. The portions of the graphical user interface shown in broken lines form no part of the claimed design.

1 Claim, 4 Drawing Sheets
